Des. 214,416
Patented June 10, 1969

214,416

ELECTRIC SHAVER TRAVEL CASE

William J. Rakocy, Clifton, N.J., assignor to Ronson Corporation, Woodbridge, N.J., a corporation of New Jersey

Filed May 15, 1968, Ser. No. 11,948

Term of patent 14 years

Int. Cl. D28—03

U.S. Cl. D95—3

FIG. 1 is a front perspective view of an electric shaver travel case showing my new design.

FIG. 2 is a front view thereof.

FIG. 3 is a top view thereof.

FIG. 4 is a bottom view thereof.

FIG. 5 is a right-side view thereof.

FIG. 6 is a rear view thereof.

FIG. 7 is a left-side view thereof.

I claim:

The ornamental design for an electric shaver travel case, substantially as shown.
